RAILWAY BRAKING APPARATUS

Harold C. Clausen, Swissvale, Pa., assignor to The Union Switch & Signal Company, Swissvale, Pa., a corporation of Pennsylvania

Application April 22, 1933. Serial No. 667,384

22 Claims. (Cl. 303—20)

My invention relates to railway braking apparatus, and particularly to braking apparatus of the type comprising wheel engaging braking bars located beside a track rail, and movable toward and away from the rail into braking and non-braking positions. More particularly my invention relates to apparatus of the type described wherein the braking bars are arranged to be moved to their braking positions by means of one or more fluid pressure operated motors, and to be restored to their non-braking positions by suitable biasing means such as gravity.

Specifically, my invention relates to means for controlling the supply of fluid pressure to, and exhaust of fluid pressure from, the fluid pressure motor or motors of braking apparatus of the type described when the braking apparatus is to be utilized in connection with a duplex pressure fluid distribution system such as is disclosed and claimed in an application for Letters Patent of the United States, Serial No. 639,434, filed by Herbert L. Bone, on October 25, 1932, and one object of my invention is to improve and simplify the control means disclosed in the said Bone application.

Other objects of my invention will appear as the description proceeds.

I will describe two forms of apparatus embodying my invention, and will then point out the novel features thereof in claims.

In the accompanying drawings, Fig. 1 is a view, partly sectioned and partly diagrammatic, illustrating one form of apparatus embodying my invention. Fig. 2 is a view similar to Fig. 1, but showing a modified form of the apparatus illustrated in Fig. 1, which modified form of apparatus also embodies my invention.

Similar reference characters refer to similar parts in both views.

Referring to the drawings, the reference character 1 designates one track rail of a stretch of railway track, which track rail, as here shown, is secured to a rail support 2 mounted on an adjacent pair of the usual crossties 3, only one cross-tie being visible in the drawings. Associated with the rail 1 is a car retarder comprising two braking bars A¹ and A² located on opposite sides of the rail. Each of these braking bars comprises, as usual, a brake beam 4 and a brake shoe 5.

The braking bars A¹ and A² are arranged to be moved toward and away from the rail 1 through the medium of a lever 6 which is pivotally mounted at one end on a pivot pin 8 carried by the rail support 2, and a lever 7 which is pivotally mounted intermediate its ends on the pivot pin 8. The

lever 6 is inclined upwardly and extends away from the rail 1 and is provided in its upper surface with a groove 6^a which receives the braking bar A¹. The one end 7^a of the lever 7 is likewise inclined upwardly and extends away from the rail 1 at the opposite side of the rail from the lever 6, and the other end 7^b of the lever 7 is inclined downwardly and extends away from the rail 1 below the lever 6. The end 7^a of the lever 7 is provided in its upper surface with a groove 7^c similar to the groove 6^a in the lever 6, which groove receives the braking bar A². The parts are so proportioned that if the outer or free ends of the levers 6 and 7 are moved apart, the braking bars will be moved toward the rail 1 into their effective or braking positions. When the braking bars occupy their braking positions, the brake shoes 5 will engage the opposite side faces of a car wheel traversing rail 1, and will retard the speed of the car. The center of gravity of the lever 6 and braking bar A¹ is considerably to the right of the pivot pin 8, so that this lever will normally tend to rotate in a clockwise direction about the pivot pin. Similarly, the center of gravity of the lever 7 and braking bar A² is to the left of the pivot pin 8 so that this lever will normally tend to rotate in a counter-clockwise direction about the pivot pin. It will be apparent, therefore, that when no force is applied to the free ends of the levers 6 and 7 to move them apart, the free ends of these levers will move toward each other, thereby moving the braking bars to their ineffective or non-braking positions in which they are illustrated in the drawings.

The levers 6 and 7 are moved apart to move the braking bars to their braking positions by means of a fluid pressure motor M comprising a cylinder 9 containing a piston 10 which drives a piston rod 11. The cylinder 9 is pivotally connected with the free end of the lever 6 by means of trunnions 12 formed on the side of the cylinder and extending through bifurcations 13 formed on the lever 6, while the piston rod 11 is connected at its free end with the free end 7^b of the lever 7 by means of an adjustable eyebolt 14 and a pivot pin 15. Fluid pressure may be admitted to the cylinder 9 between the upper end of the cylinder and the piston 10 through an opening 16 which is threaded to receive a pipe 17. When fluid pressure is admitted to the cylinder 9 through the pipe 17 and opening 16, the piston 10 will be forced downwardly and the cylinder 9 upwardly, thereby separating the levers 6 and 7, and hence moving the braking bars toward their effective or braking positions.

being obvious that when the braking bars are moved to their braking positions, they will exert a braking force which is proportional to the pressure of the fluid supplied to the cylinder 9.

5 It should be pointed out that while in the drawings I have shown only one operating unit for the braking bars A¹ and A², in actual practice these braking bars are provided with a plurality of other similar units, disposed at 10 spaced intervals along the bars, substantially as shown in an application for Letters Patent of the United States Serial No. 516,883, filed by Herbert L. Bone, on Feb. 19, 1931, for Railway braking apparatus. It should also be pointed 15 out, that as a general rule, the car retarder will consist not only of braking bars associated with one track rail, as shown in the drawings, but also also of other similar braking bars associated with the opposite track rail as well, the length of the 20 braking bars associated with both track rails being determined by the speed and the weight of the cars to be retarded, the lengths of the cars, the number of wheels on the cars, etc.

The motor M is controlled by three magnet 25 valves, designated by the reference characters V¹, V² and V³, respectively, and each comprising a valve stem 18 biased to an upper position by means of a spring 19, and provided with a winding 20 and an armature 21. When valve V¹ is 30 energized, as shown in the drawings, valve stem 18 of this valve moves downwardly against the bias exerted by the associated spring 19, and under these conditions, a pipe 22 which communicates with the pipe 17 is connected with 35 atmosphere, through a port 23, thus connecting the region of cylinder 9 between the piston 10 and the upper end of the cylinder with atmosphere. When valve V¹ is deenergized, however, 40 valve stem 18 of this valve is moved upwardly by the associated spring 19, and pipe 22 is then disconnected from port 23, so that the region of cylinder 9 between piston 10 and the upper end of the cylinder is then disconnected from atmosphere. When valve V² is energized, valve 45 stem 18 of this valve moves downwardly, and a pipe 24 which communicates with the pipe 22 is then connected with a pipe 25 forming part of a low pressure fluid distribution system. This low pressure fluid distribution system is 50 constantly supplied with fluid pressure, usually air, from a relatively low pressure source, not shown in the drawings, and it follows that when valve V² is energized, the region of cylinder 9 between piston 10 and the upper end of the cylinder is 55 supplied with fluid pressure from the low pressure system. When valve V² is deenergized, however, pipe 24 is disconnected from pipe 25 and is 60 connected with a pipe 26 which leads to the valve V³. When valve V³ is energized, valve stem 18 of this valve moves downwardly and connects pipe 26 with a pipe 27 forming part of a high pressure fluid distribution system, which latter distribution system is constantly supplied with 65 fluid pressure, usually air, from a relatively high pressure source. When valve V³ is deenergized, however, valve stem 18 of this valve moves to its upper position and disconnects the pipe 26 from the pipe 27. It will be seen, therefore, that when valve V³ is energized and valve V² is deenergized, the region of cylinder 9 between the 70 piston 10 and the upper end of the cylinder is supplied with fluid pressure from the high pressure system, but that when valve V³ is deenergized, the supply of fluid pressure from the high pressure system to cylinder 9 is cut off.

The pressure of the fluid in the low pressure system may be maintained at any suitable pressure, but for purposes of illustration, I will assume that this pressure is maintained at approximately 50 pounds per square inch. Likewise, the pressure of the fluid in the high pressure system may be maintained at any desired pressure but for purposes of illustration I will assume that this pressure is maintained at approximately 100 pounds per square inch.

80 The valves V are controlled in part by two pressure responsive devices P²⁰⁻³⁰ and P⁷⁰⁻⁸⁰, each comprising a Bourdon tube 28 connected to the pipe 17, and hence subjected to the pressure of the fluid in the region of cylinder 9 between the piston 10 and the upper end of the cylinder. Each Bourdon tube 28 controls two contacts 29-29^a and 29-29^b. The pressure responsive devices P²⁰⁻³⁰ and P⁷⁰⁻⁸⁰ are so constructed that 85 they will operate successively as the pressure of the fluid in the region of cylinder 9 between piston 10 and the upper end of the cylinder increases. For example, for all pressures below 20 pounds per square inch, contact 29-29^a of each of these devices is closed. If the pressure exceeds 20 pounds per square inch, however, contact 29-29^a of device P²⁰⁻³⁰ opens, and if the pressure exceeds 30 pounds per square inch, contact 29-29^b of device P²⁰⁻³⁰ closes. In similar manner, the pressure device P⁷⁰⁻⁸⁰ is adjusted to open its contact 90 29-29^a at 70 pounds per square inch, and to close its contact 29-29^b at 80 pounds per square inch. Of course, these specific pressures are not essential, but are only mentioned for purposes of explanation.

95 The valves V are controlled by means of two pneumatically operated transfer switches S¹ and S². Referring first to the switch S¹, this switch comprises a housing 30 provided with a chamber 31 into the upper end of which a switch operating 100 rod 32 extends. The lower end of the rod 32 is connected to two spaced diaphragms 33 and 34 of different sizes, the diaphragm 33 being smaller than the diaphragm 34. The portion of the chamber 31 between the diaphragms 33 and 34 105 is constantly connected with atmosphere by means of a port 35, while the portion of the chamber 31 below the diaphragm 33 is connected with the pipe 25 by means of a pipe 37, and the portion of the chamber 31 above the diaphragm 34 is connected with the pipe 22. It will be apparent, therefore, that the lower side of the diaphragm 33 is constantly subjected to the pressure of the fluid 110 in the low pressure distribution system, while the upper side of the diaphragm 34 is subjected to the pressure of the fluid in the upper end of cylinder 9 of motor M. As will be seen from an inspection of the drawings, the two diaphragms 33 and 34 are normally bowed upwardly, and the parts are so proportioned that when the net force 115 resulting from the difference between the pressure exerted on diaphragm 33 and the pressure exerted on diaphragm 34 is sufficient to move the diaphragms, they will move with a snap action, and will under no condition stop in mid stroke. The relative sizes of the two diaphragms 33 and 34 are such that the diaphragms will snap to their 120 lower positions when the pressure in the upper end of cylinder 9 reaches a value slightly below that in the low pressure distribution system. It will be apparent, therefore, that the diaphragms 125 will not return to their normal positions after they have once been snapped downwardly until the pressure in the cylinder 9 has been reduced a certain amount below that in the low pressure 130 system. The switch S² is similar in construction to the switch S¹, but is controlled by the pressure in the cylinder 9, and is connected with the pipe 25. The switch S² is 135 controlled by the pressure responsive device P⁷⁰⁻⁸⁰, which is connected with the pipe 17. The switch S² is so constructed that when the pressure in the cylinder 9 reaches 140 the pressure responsive device P⁷⁰⁻⁸⁰, the switch S² will open, and the switch S¹ will close. The switch S¹ is controlled by the pressure responsive device P²⁰⁻³⁰, which is connected with the pipe 17. The switch S¹ is 145 so constructed that when the pressure in the cylinder 9 reaches the pressure responsive device P²⁰⁻³⁰, the switch S¹ will open, and the switch S² will close. The switch S² is controlled by the pressure responsive device P⁷⁰⁻⁸⁰, which is connected with the pipe 17. The switch S² is 150 so constructed that when the pressure in the cylinder 9 reaches the pressure responsive device P⁷⁰⁻⁸⁰, the switch S² will open, and the switch S¹ will close.

distribution system. For example, the parts will usually be so proportioned that when the pressure in the low pressure distribution system is 50 pounds per square inch, the diaphragms will snap to their lowermost positions as soon as the pressure of the fluid in cylinder 9 has increased to about 48 pounds per square inch, and will subsequently remain in their lowermost positions until the pressure in cylinder 9 has been reduced to approximately 40 pounds per square inch. The upper end of the operating rod 32 carries a contact member 38 which cooperates with three fixed contact members 39, 40 and 41 in such manner that when the diaphragms 33 and 34 occupy their upper or normal positions, the contact members 38 will engage the fixed contact members 39 and 40 to close a contact 39-38-40, but that when the diaphragms 33 and 34 occupy their lowermost positions, the contact member 38 will then engage the fixed contact members 39 and 41 to close a contact 39-38-41.

The transfer switch S² is similar to the switch S¹ with the exception that the diaphragms 33 and 34 of this switch are normally bowed downwardly and are designed to operate at somewhat different pressures from the pressures at which the switch S² operates, as I will explain presently. The region of diaphragm chamber 31 of this switch below the diaphragm 33 is connected with the pipe 22 by means of a pipe 42, so that the lower side of the diaphragm 33 is constantly subjected to the pressure of the fluid in the cylinder 9. The region of diaphragm chamber 31 above the diaphragm 34 is connected with the pipe 25 by means of a pipe 43, and it follows that the upper side of the diaphragm 34 is constantly subjected to the pressure of the fluid in the low pressure distribution system. The parts are so proportioned that when the pressure in the upper end of cylinder 9 increases to a value which is a predetermined amount above that in the low pressure system, the diaphragms 33 and 34 will snap upwardly, and that when the pressure in the cylinder 9 is subsequently decreased to a predetermined pressure which is slightly above that in the low pressure system, the diaphragms will snap downwardly to the positions in which they are shown. After the diaphragms have snapped downwardly, they will, of course, remain in their lowermost positions until the pressure in the cylinder 9 is again increased to a value which is high enough to cause them to snap upwardly. For example, the parts will usually be so proportioned that when the pressure of the fluid in the low pressure system is 50 pounds per square inch, the diaphragms 33 and 34 will snap upwardly when the pressure of the fluid in cylinder 9 has increased to approximately 60 pounds per square inch and will subsequently remain in their upper positions until the pressure of the fluid in cylinder 9 has again decreased to approximately 52 pounds per square inch. It is, of course, understood that the specific pressures mentioned in describing the operation of the switches S¹ and S² are not necessarily the exact pressures at which operation of these switches will occur, but are stated for purposes of illustration only. The operating rod 32 of the switch S² controls two contacts 39-38-41 and 39-38-40 which are similar in all respects to the corresponding contacts of the switch S¹.

The valves V¹, V² and V³ are further controlled by a manually operable lever L capable of assuming five positions, indicated by the reference characters p¹ to p⁵, inclusive. Attached to the lever L

is a contact arm 44 which is selectively moved into engagement with a plurality of fixed contacts 45 to 49, inclusive, in response to movement of the lever to its various positions.

Lever L will usually be located at a point remote from the braking apparatus, as in the control cabin of a classification yard car retarder system, and will be connected with the braking apparatus by means of line wires extending from the control cabin to the braking apparatus.

As shown in the drawings, lever L occupies its p¹ or "off" position, and under these conditions, a circuit is completed for valve V¹, which circuit passes from a suitable source of current, here shown as a battery B, through wire 50, contact 44-45 of lever L, line wire 51, contact 39-38-41 of transfer switch S², winding 20 of valve V¹, wires 52 and 53, and line wire 54 back to battery B. Valve V¹ is therefore energized, so that the upper end of motor M is vented to atmosphere. The valves V² and V³ are both deenergized, and the supply of fluid to motor M from both the high and low pressure distribution systems is accordingly cut off. Since the supply of fluid to motor M is cut off, and the motor is vented to atmosphere, the braking bars are held by gravity in their non-braking positions.

I will now assume that the operator wishes to cause the car retarder to exert a comparatively light braking force. To do this, he moves lever L from its p¹ to its p² position, thereby opening contact 44-45 of the lever and closing contact 44-46. The opening of contact 44-45 interrupts the circuit which was previously closed for valve V¹ at this contact, and valve V¹ therefore becomes deenergized and disconnects pipe 22 from atmosphere, thus disconnecting the region of cylinder 9 of motor M between piston 10 and the upper end of the cylinder from atmosphere. The closing of contact 44-46 of lever L completes a circuit for valve V², and current flows from battery B through wire 50, contact 44-46 of lever L, line wire 55, contact 29-29^a of pressure responsive device P²⁰⁻³⁰, wires 56 and 57, winding 20 of valve V², wire 53, and line wire 54 back to battery B. Valve V² therefore becomes energized, and connects pipe 22 with pipe 25, so that fluid pressure from the low pressure distribution system is now supplied to the upper end of cylinder 9 of motor M. The fluid pressure thus supplied to cylinder 9 forces piston 10 downwardly and cylinder 9 upwardly in the manner previously described, thereby moving the braking bars toward their braking positions. When the pressure in cylinder 9 increases to 20 pounds per square inch, contact 29-29^a of pressure responsive device P²⁰⁻³⁰ will open and will interrupt the circuit just traced for valve V². Valve V² will then become deenergized and will cut off the supply of fluid pressure to cylinder 9 until the pressure of the fluid again decreases below 20 pounds per square inch. If the pressure of the fluid in the upper end of cylinder 9 increases to 30 pounds per square inch for any reason, contact 29-29^b of pressure responsive device P²⁰⁻³⁰ will become closed, and will complete another circuit for valve V¹, this latter circuit passing from battery B through wire 50, contact 44-46 of lever L, line wire 55, contact 29-29^b of pressure responsive device P²⁰⁻³⁰, wire 58, contact 39-38-41 of transfer switch S², winding 20 of valve V¹, wires 52 and 53, and line wire 54 back to battery B. Valve V¹ will then become energized and will vent fluid from the upper end of cylinder 9 to atmosphere until the pressure of the

fluid in this region of the cylinder again decreases to 30 pounds per square inch, at which time contact 29-29^b of pressure responsive device P⁷⁰⁻⁸⁰ will open and will deenergize valve V¹. It will be seen, therefore, that when lever L occupies its p² position, the braking bars will be held in their braking positions by a pressure of between 20 and 30 pounds per square inch.

I will next assume that the operator desires to cause the braking bars to exert a somewhat higher braking force. He therefore moves lever L from its p² to its p³ position. Under these conditions, valve V² becomes energized, and constantly remains energized as long as the lever remains in its p³ position, by virtue of a circuit which passes from battery B through wire 50, contact 44-47 of lever L, line wire 59, wires 56 and 57, winding 20 of valve V², wire 53, and line wire 54 back to battery B. When valve V² becomes energized, fluid from the low pressure source is, of course, supplied to the upper end of cylinder 9 of motor M, and since this valve now remains energized, it will be apparent that the pressure of the fluid in the upper end of cylinder 9 will build up to the full line pressure of the low pressure source. It follows, that under these conditions, the braking bars will be held in their braking positions by the full pressure of the low pressure source. Shortly before the pressure of the fluid in motor M reaches the full pressure of the low pressure source, the diaphragms 33 and 34 of transfer switch S¹ will snap downwardly to their lowermost positions, thus opening contact 39-38-40 of this transfer switch and closing contact 39-38-41. The operation of these contacts under these conditions, however, will have no immediate effect upon the operation of the remainder of the apparatus.

If a still higher braking force is desired, the operator will move lever L from its p³ position to its p⁴ position. When he does this, all circuits previously traced for the valves V¹ and V² will be interrupted, and a circuit for valve V³ will become closed, this latter circuit passing from battery B through wire 50, contact 44-48 of lever L, line wire 62, contact 29-29^a of pressure responsive device P⁷⁰⁻⁸⁰, wires 60 and 61, contact 39-38-41 of transfer switch S¹, winding 20 of valve V³, and line wire 54 back to battery B. Valve V³ will therefore become energized, and since valve V² is now deenergized, fluid pressure from the high pressure source will be supplied to the upper end of cylinder 9 of motor M. When the pressure in the upper end of cylinder 9 increases to 60 pounds per square inch, the diaphragms of transfer switch S² will snap to their uppermost positions, thus opening contact 39-38-41 of switch S² and closing contact 39-38-40 of switch S². The operation of these contacts under these conditions, however, will have no immediate effect on the remainder of the apparatus. When the pressure of the fluid in the upper end of cylinder 9 of motor M increases to 70 pounds per square inch, contact 29-29^a of pressure responsive device P⁷⁰⁻⁸⁰ will open, and will interrupt the circuit just traced for valve V³. Valve V³ will then become deenergized, and will cut off the supply of fluid pressure to the upper end of cylinder 9 of motor M. If the pressure in the upper end of cylinder 9 of motor M increases to 80 pounds per square inch, contact 29-29^b of pressure responsive device P⁷⁰⁻⁸⁰ will become closed, and will complete another circuit for valve V², this latter circuit passing from battery B through wire 50, contact 44-48 of lever L, line wire 62,

contact 29-29^b of pressure responsive device P⁷⁰⁻⁸⁰, wire 58, contact 39-38-40 of switch S², wire 57, winding 20 of valve V², wire 53, and line wire 54 back to battery B. Valve V² will therefore become energized, and since the pressure of the fluid in the upper end of cylinder 9 of motor M is now above that of the fluid in the low pressure system, fluid will be vented from the motor into the low pressure system until the pressure decreases sufficiently to permit contact 29-29^b of pressure responsive device P⁷⁰⁻⁸⁰ to open and deenergize valve V². It follows, therefore, that when lever L occupies its p⁴ position, the braking bars will be held in their braking positions by a pressure of between 70 and 80 pounds per square inch.

I will now assume that the operator, instead of moving lever L to its p⁴ position from its p³ position, moves the lever to its p⁴ position directly from its p¹ or p² position. Under these conditions, when the lever first reaches its p⁴ position, the diaphragms of transfer switch S¹ will still occupy their upper positions so that contact 39-38-40 of this switch will be closed and contact 39-38-41 will be open, and as a result, a circuit passing from battery B through wire 50, contact 44-48 of lever L, line wire 62, contact 29-29^a of pressure responsive device P⁷⁰⁻⁸⁰, wires 60 and 61, contact 39-38-40 of transfer switch S¹, wire 63, winding 20 of valve V², wire 53, and line wire 54 back to battery B. Valve V² will therefore become energized and will admit fluid to the upper end of cylinder 9 of motor M from the low pressure distribution system in the manner previously described. When the pressure of the fluid in motor M increases to 48 pounds per square inch, the diaphragms of transfer switch S¹ will then snap downwardly to their lowermost positions, thus opening contact 39-38-40 of switch 100

S¹ and closing contact 39-38-41. The opening of contact 39-38-40 will interrupt the circuit just described for valve V², while the closing of contact 39-38-41 will complete the previously described circuit for valve V³ including this contact, contact 35-48 of lever L, and contact 29-29^a of pressure responsive device P⁷⁰⁻⁸⁰. Valve V² will therefore become deenergized, and will cut off the supply of fluid pressure to cylinder 9 of motor M from the low pressure distribution system, and valve V³ will become energized and will admit fluid pressure to cylinder 9 of motor M from the high pressure distribution system. After valve V³ once becomes energized under these conditions, the operation of the apparatus will then be exactly the same as it is after this valve becomes energized when Lever L is moved to its p⁴ position from its p³ position. It will be apparent, therefore, that when lever L is moved directly from its p¹ or p² position to its p⁴ position, valve V² will first become energized, and will admit fluid pressure from the low pressure distribution system to the upper end of cylinder 9 of motor M until the pressure in the cylinder increases to 48 pounds per square inch, after which valve V² will become deenergized and valve V³ will become energized. When valve V³ becomes energized, any further fluid which is supplied to motor M will, of course, be supplied from the high pressure distribution system.

If the operator desires to cause the braking bars to exert their maximum braking force, he will move lever L to its p⁵ position. When he does this, if the lever had previously occupied its p³ or p⁴ position long enough to permit the 150

pressure of the fluid in the upper end of cylinder 9 of motor M to build up to the value at which transfer switch S¹ opens its contact 39-38-40 and closes its contact 39-38-41, valve 5 V³ will immediately become energized and will admit fluid pressure to the upper end of cylinder 9 of motor M from the high pressure distribution system, the circuit for valve V³ under these conditions passing from battery B through wire 50, contact 44-49 of lever L, line wire 64, wire 61, contact 39-38-41 of transfer switch S¹, winding 20 of valve V³, and line wire 54 back to battery B. If, however, when lever L is moved to its p⁵ position, the lever had previously occupied its p¹ or p² position, so that when the lever reaches its p⁵ position, the pressure in the upper end of cylinder 9 of motor M is still below the pressure at which the transfer switch S¹ opens its contact 39-38-40 and closes its contact 10 39-38-41, valve V² will then become energized and will admit fluid pressure to cylinder 9 of motor M from the low pressure distribution system until the pressure in the cylinder builds up to the pressure at which transfer switch S¹ opens its contact 39-38-40 and closes its contact 15 39-38-41, whereupon, valve V³ will then become energized by virtue of the circuit just traced above. The circuit for valve V² under these latter conditions passes from battery B through wire 50, contact 44-49 of lever L, line wire 64, wire 61, contact 39-38-40 of transfer switch S¹, wire 63, winding 20 of valve V², wire 53, and line wire 54 back to battery B. It will be apparent from an inspection of the drawings 20 that after valve V³ once becomes energized under these conditions, it will subsequently remain energized as long as lever L remains in its p⁵ position, so that the braking bars will be held in their braking positions by the full pressure of 25 the high pressure distribution system.

I will now assume that lever L has been moved to its p⁵ position to cause the braking bars to exert their maximum braking force, and that the operator wishing to reduce the braking force exerted by the braking bars, moves the lever to its p² position. This movement of the lever will interrupt the circuit which was previously closed for valve V³ and will complete a circuit for valve V² which latter circuit passes from battery B through wire 50, contact 44-46 of lever L, line wire 55, contact 29-29^b of pressure responsive device P²⁰⁻³⁰, wire 58, contact 39-38-40 of transfer switch S², wire 57, winding 20 of valve V², wire 53, and line wire 54 back to battery B. Valve V³ will therefore become deenergized and will disconnect cylinder 9 from the high pressure distribution system, and valve V² will become energized and will connect cylinder 9 with the low pressure distribution system. When cylinder 9 becomes connected with the low pressure distribution system, the pressure of the fluid in the motor will, of course, be above that in the low pressure system, and fluid from cylinder 9 will therefore be vented into the low pressure distribution system. As soon as the pressure of the fluid in cylinder 9 has decreased to 52 pounds per square inch, transfer switch S² will open its contact 39-38-40 and close its contact 39-38-41, thereby interrupting the circuit just traced for valve V² and completing the previously described circuit for valve V¹ including contact 39-38-41 of switch S² and contact 29-29^b of pressure responsive device P²⁰⁻³⁰. Valve V² will then become deenergized and will disconnect cylinder 9 from the low pressure distribution system, and valve V¹ will become energized and will connect cylinder 9 with atmosphere. When the pressure of the fluid in cylinder 9 has decreased to 40 pounds per square inch, transfer switch S¹ will operate to open its contact 39-38-40 and to close its contact 39-38-41, but the operation of this switch under these conditions will have no effect on the remainder of the apparatus. The pressure of the fluid in cylinder 9 will now continue to decrease until the pressure has decreased to 30 pounds per square inch, at which time pressure responsive device P²⁰⁻³⁰ will open its contact 29-29^b and deenergize valve V². From this point on, the operation of the apparatus will be the same as it is after the pressure of the fluid in cylinder 9 has built up to the value at which contact 29-29^a of pressure responsive device P²⁰⁻³⁰ opens when lever L is moved to its p² position from its p¹ position.

I will now assume that the braking bars are in their braking positions, and that the operator wishes to restore them to their non-braking positions. He will therefore move lever L to its p¹ or "off" position. When he does this, if the pressure of the fluid in the upper end of cylinder 9 of motor M is then above the pressure at which transfer switch S² opens its contact 39-38-40 and closes its contact 39-38-41, as will be the case as lever L previously occupied its p⁴ or p⁵ position, valve V² will first become energized and will vent fluid from motor M into the low pressure distribution system until the pressure of the fluid in the motor decreases to the pressure at which transfer switch S² opens its contact 39-38-40 and closes its contact 39-38-41, whereupon valve V¹ will become energized and will vent the remainder of the fluid in the motor to atmosphere. If, however, when the lever is moved to its p¹ position, the pressure of the fluid in cylinder 9 is below the pressure at which transfer switch S² opens its contact 39-38-40 and closes its contact 39-38-41, as will be the case as the lever previously occupied its p² or p³ position, valve V¹ will immediately become energized and will vent fluid from cylinder 9 to atmosphere. The circuit over which valve V² becomes energized under the above conditions passes from battery B through wire 50, contact 44-45 of lever L, line wire 51, contact 39-38-40 of transfer switch S², wire 57, winding 20 of valve V², wire 53, and line wire 54 back to battery B. The circuit over which valve V² becomes energized under the above conditions has previously been described and need not therefore be repeated here. It should be pointed out that if the pressure of the fluid in cylinder 9 of motor M has been above the pressure at which transfer switch S² opens its contact 39-38-40 and closes its contact 39-38-41 at any time prior to the movement of lever L to its p¹ position, this switch will operate to open its contact 39-38-41 and close its contact 39-38-40 as soon as the pressure in motor M has decreased to 40 pounds per square inch. As the pressure in cylinder 9 of motor M decreases, the braking bars will return to their non-braking positions by gravity, and when the braking bars reach their non-braking positions, all parts will be restored to the positions in which they are shown in the drawings.

It should be particularly pointed out that while in the foregoing description, I have described the operation of the apparatus for only a few of the principal movements of lever L, the operation of the apparatus for the remainder of the possible movements of the lever is similar to that already

described, and it is believed that this operation will be understood from an inspection of the drawings and from the foregoing description without further detailed explanation.

- 5 Referring now to Fig. 2, as here shown, lever L is provided with a second contact arm 44^a adapted to engage a selected one of a plurality of fixed contacts in such manner that when contact arm 44 engages a given fixed contact, the contact 10 arm 44^a will engage a similar fixed contact designated by a similar reference character with the distinguishing exponent *a*. For example, when lever L occupies its *p*¹ position, in which position it is illustrated in the drawings, so that contact 15 arm 44 engages fixed contact 45, contact arm 44^a will engage fixed contact 45^a; and when lever L occupies its *p*² position, so that contact arm 44 engages fixed contact 46, contact arm 44^a will engage fixed contact 46^a. Furthermore, as shown 20 in Fig. 2, the circuits for controlling the valves V have been modified somewhat, and rectifiers have been included in certain ones of these circuits in order to decrease the number of line wires between the control point and the braking apparatus, and to prevent improper operation of 25 the valves V in the event that the contacts of one of the pressure responsive devices becomes short-circuited, as by condensation of moisture on the contacts.
- 30 The operation of the apparatus shown in Fig. 2 is as follows: When lever L occupies its *p*¹ or "off" position, valves V² and V³ are both deenergized, and valve V¹ is energized over a circuit which passes from battery B through wire 50, contact 35 44—45 of lever L, line wire 51, an asymmetric unit R¹ in its low resistance direction, wire 65, contact 39—38—41 of transfer switch S², winding 20 of valve V¹, wires 52 and 53, and line wire 54 back to battery B. Since valves V² and V³ 40 are deenergized, the supply of fluid pressure to cylinder 9 of motor M from both the high and low pressure distribution systems is cut off, and since valve V¹ is energized, the upper end of cylinder 9 of motor M is vented to atmosphere. The 45 braking bars are therefore held in their non-braking positions by gravity. Furthermore, since the upper end of motor M is vented to atmosphere, contact 39—38—40 of transfer switch S¹, contact 39—38—41 of transfer switch S², and the 50 contacts 29—29^a of the pressure responsive devices P are all closed, while contact 39—38—41 of transfer switch S¹, contact 39—38—40 of transfer switch S², and contacts 29—29^b of the pressure responsive devices P are all open.
- 55 If, now, lever L is moved to its *p*² position, valve V¹ will become deenergized, and valve V² will become energized over a circuit which passes from battery B through wire 50, contact 44—46 of lever L, line wire 55, contact 29—29^a of pressure responsive device P^{20—30}, wires 56 and 57, winding 20 of valve V², wire 53, and line wire 54 back to battery B. The deenergization of valve V¹ will disconnect the upper end of cylinder 9 of motor M from atmosphere, while the 65 energization of valve V² will connect the upper end of cylinder 9 with pipe 25, so that fluid pressure will then be supplied to cylinder 9 from the low pressure distribution system, thus moving the braking bars to their braking positions. 70 When the pressure of the fluid in cylinder 9 increases to 20 pounds per square inch, contact 29—29^a of pressure responsive device P^{20—30} will open and will deenergize valve V², and if the pressure of the fluid in cylinder 9 increases to 75 30 pounds per square inch, contact 29—29^b of

pressure responsive device P^{20—30} will become closed and will complete another circuit for valve V¹, this latter circuit passing from battery B through wire 50, contact 44—46 of lever L, line wire 55, contact 29—29^b of pressure responsive device P^{20—30}, wire 66, asymmetric unit R⁴ in its low resistance direction, wire 58, contact 39—38—41 of transfer switch S², winding 20 of valve V¹, wires 52 and 53, and line wire 54 back to battery B. Valve V¹ will therefore become energized, and will vent fluid from cylinder 9 until the pressure of the fluid in the cylinder decreases sufficiently to cause contact 29—29^b of pressure responsive device P^{20—30} to open and deenergize valve V¹. It will be seen, therefore, that with the apparatus shown in Fig. 2, when lever L is moved to its *p*² position, the braking bars will be held in their braking positions by a pressure of between 20 and 30 pounds per square inch in the same manner as with the apparatus shown in Fig. 1.

If lever L is moved from its *p*² position to its *p*³ position, the circuit last traced for valve V² will become interrupted, and another circuit for valve V² will become closed, this latter circuit passing from a suitable source, here shown as a battery B¹, through line wire 54, wire 53, winding 20 of valve V², wires 57, 56 and 67, an asymmetric unit R² in its low resistance direction, line wire 51, wire 68, contact 44^a—47^a of lever L, and wire 69 back to battery B¹. It will be noted that this circuit is controlled entirely by contact 44^a—47^a of lever L, and it follows therefore that valve V² will now remain energized as long as lever L remains in its *p*³ position, and the braking bars will therefore be held in their braking positions under these conditions by fluid at the full pressure of the low pressure distribution system. Shortly before the pressure of the fluid in cylinder 9 of motor M reaches the full pressure of the low pressure distribution system, transfer switch S¹ will open its contact 39—38—41 and close its contact 39—38—40 in the manner previously described. The operation of these contacts under these conditions, however, will have no immediate effect on the remainder of the apparatus.

I will next assume that lever L is moved from its *p*³ position to its *p*⁴ position. Under these conditions, valve V² will become deenergized and valve V³ will become energized, thus causing fluid pressure to be supplied to the upper end of cylinder 9 of motor M from the high pressure distribution system. The circuit over which valve V³ becomes energized under these conditions passes from battery B through wire 50, contact 44—48 of lever L, line wire 62, wire 71, contact 29—29^a of pressure responsive device P^{70—80}, wires 60 and 61, contact 39—38—41 of transfer switch S¹, winding 20 of valve V³, and line wire 54 back to battery B. When the pressure of the fluid in the upper end of cylinder 9 increases to 60 pounds per square inch, transfer switch S² will open its contact 39—38—41 and close its contact 39—38—40. The operation of these contacts, however, will have no immediate effect on the remainder of the apparatus. When the pressure of the fluid in the upper end of cylinder 9 increases to 70 pounds per square inch, contact 29—29^a of pressure responsive device P^{70—80} will open, and will interrupt the circuit just traced for valve V³. Valve V³ will then become deenergized, thereby cutting off the supply of fluid pressure to the upper end of cylinder 9. If the pressure in the upper end of cylinder 9

cylinder 9 increases to 80 pounds per square inch, contact 29-29^b of pressure responsive device P⁷⁰⁻⁸⁰ will become closed, and will complete another circuit for valve V² which circuit passes from battery B, through wire 50, contact 44-48 of lever L, line wire 62, wire 71, contact 29-29^b of pressure responsive device P⁷⁰⁻⁸⁰, wire 66, asymmetric unit R⁴ in its low resistance direction, wire 58, contact 39-38-40 of transfer switch S², wire 57, winding 20 of valve V², wire 53, and line wire 54 back to battery B. Valve V² will therefore become energized and will vent fluid from the upper end of cylinder 9 into the low pressure distribution system. Valve V² will 15 continue to vent fluid to the low pressure system until the pressure again decreases to 80 pounds per square inch, at which time contact 29-29^b of pressure responsive device P⁷⁰⁻⁸⁰ will open and will deenergize valve V².

If lever L instead of being moved to its p⁴ position from its p³ position is moved to its p⁴ position directly from its p¹ or p² position, contact 39-38-40 of transfer switch S¹ will be closed when the lever reached its p⁴ position, and under these conditions, valve V² will become energized over a circuit which passes from battery B through contact 44-48 of lever L, line wire 62, wire 71, contact 29-29^a of pressure responsive device P⁷⁰⁻⁸⁰, wires 60 and 61, contact 39-38-40 of transfer switch S¹, winding 20 of valve V², wire 53, and line wire 54 back to battery B. Fluid pressure will therefore be supplied to cylinder 9 of motor M from the low pressure source until the pressure of the fluid in the motor increases to 48 pounds per square inch. When this happens, switch S¹ will open its contact 39-38-40, and close its contact 39-38-41, thereby interrupting the circuit which was previously closed for valve V² and completing the previously described circuit for valve V³. After valve V³ once becomes energized, the operation of the apparatus will then be the same as when lever L is moved to its p⁴ position from its p³ position. It follows, therefore, that if lever L is moved to its p⁴ position directly from its p¹ or p² position, cylinder 9 of motor M will be supplied with fluid from the low pressure distribution system until the pressure of the fluid builds up to substantially the pressure of the low pressure distribution system, after which the motor will then be supplied with fluid pressure from the high pressure distribution system until the pressure increases to the value at which contact 29-29^a of pressure responsive device P⁷⁰⁻⁸⁰ opens. Furthermore, if the pressure in the upper end of cylinder 9 of motor M under the conditions just described increases to 80 pounds per square inch, valve V² will become energized and will vent fluid from the motor into the low pressure distribution system until the pressure in the motor again decreases to 80 pounds.

If lever L is first moved to its p³ or p⁴ position long enough to permit the pressure in the upper end of cylinder 9 of motor M to build up to the pressure at which contact 39-38-40 of transfer switch S¹ opens and contact 39-38-41 closes, and the lever is then moved to its p⁵ position, valve V³ will immediately become energized and will subsequently remain energized as long as the lever remains in its p⁵ position, by virtue of a circuit which passes from battery B¹ through line wire 54, winding 20 of valve V³, contact 39-38-41 of transfer switch S¹, wire 61, asymmetric unit R³ in its low resistance direction, line wire 62, wire 70, contact 44-49^a of lever L, and wire 69 back to battery B¹. Under these conditions, therefore, motor M will be constantly supplied with fluid pressure from the high pressure source as long as the lever remains in its p⁵ position. If, however, lever L is moved to its p⁵ position directly from its p¹ or p² position so that contact 39-38-40 of transfer switch S¹ is still closed when the lever reaches its p⁵ position, valve V² will first become energized and will admit fluid pressure to the upper end of cylinder 9 of motor M from the low pressure distribution system until the pressure in the motor increases to the pressure at which transfer switch S¹ opens its contact 39-38-40 and closes its contact 39-38-41, after which valve V² will become deenergized and valve V³ will become energized, thereby cutting off the supply of fluid pressure to cylinder 9 from the low pressure distribution system, and admitting fluid pressure to cylinder 9 from the high pressure distribution system. The circuit over which valve V² becomes energized under these latter conditions may be traced from battery B¹ through line wire 54, wire 53, winding 20 of valve V², wire 63, contact 39-38-40 of transfer switch S¹, wire 61, asymmetric unit R³ in its low resistance direction, wires 62 and 70, contact 44^a-49^a of lever L and wire 69 back to battery B¹. The circuit over which valve V³ becomes energized under these latter conditions is the same as was previously described when lever L was moved to its p⁵ position from its p⁴ position. After valve V³ once becomes energized under these latter conditions, it will subsequently remain energized thus causing the motor to be supplied with fluid from the high pressure distribution system in the manner previously described.

If after lever L has been moved to its p⁵ position the lever is moved to its p² position, valve V³ will become deenergized and valve V² will become energized. The circuit over which valve V² becomes energized under these conditions passes from battery B through wire 50, contact 44-46 of lever L, line wire 55, contact 29-29^b of pressure responsive device P⁷⁰⁻⁸⁰, wire 66, asymmetric unit R⁴ in its low resistance direction, wire 58, contact 39-38-40 of transfer switch S², winding 20 of valve V², wire 53, and line wire 54 back to battery B. When valve V² becomes energized, fluid pressure will, of course, be vented from cylinder 9 into the low pressure distribution system. Fluid pressure will continue to be vented into the low pressure distribution system under these conditions until the pressure in cylinder 9 decreases to 52 pounds per square inch at which time transfer switch S² will open its contact 39-38-40 and close its contact 39-38-41, thereby interrupting the circuit just traced for valve V², and completing the previously described circuit for valve V¹. After the circuit for valve V¹ becomes closed under these conditions the apparatus will then function in the same manner as when lever L was moved to its p² position from its p¹ position.

I will now assume that lever L occupies its p⁵ position and that the operator moves the lever directly to its p¹ position. Under these conditions, when lever L reaches its p¹ position, contact 39-38-40 of transfer switch S² will, of course, still be closed and a circuit will therefore be completed for valve V² which passes from battery B through wire 50, contact 44-45 of lever L, line wire 51, asymmetric unit R¹ in its low resistance direction, line wire 65, contact 39-38-40 of transfer switch S², wire 57, winding 20 of valve V², wire 53 and line wire 54 back to battery B.

Fluid will therefore be vented from cylinder 9 of motor M into the low pressure distribution system until the pressure decreases to 52 pounds per square inch, whereupon the resultant operation of transfer switch S² will deenergize valve V², and will complete the previously described circuit for valve V¹. Valve V¹ will therefore become energized and will vent the remainder of the fluid in cylinder 9 of motor M to atmosphere. When the pressure of the fluid in cylinder 9 decreases to 40 pounds per square inch, transfer switch S¹ will open its contact 39-38-41 and close its contact 39-38-40, but the operation of these contacts under these conditions will have no effect on the remainder of the apparatus. As the pressure in the upper end of cylinder 9 continues to decrease, the braking bars will return to their non-braking positions by gravity, and when the braking bars reach their non-braking positions, all parts will then be restored to the positions in which they are shown in the drawings.

It should be pointed out that with the apparatus as shown in Fig. 2, if the asymmetric unit R⁴ were omitted and the contacts of one of the pressure responsive devices P became short-circuited, as by a drop of water, when lever L occupies its p¹ or "off" position, the valves V¹ and V² would then both become energized and there would be a continuous exhaust of fluid pressure from the low pressure distribution system to atmosphere. The asymmetric unit R⁴, however, prevents this from happening because it prevents the flow of current from wire 65 to the contacts of the pressure responsive devices, and hence to the valve V² under these conditions. The asymmetric units R¹ and R² are provided to permit the selective control of the valves V¹ and V² over the same pair of line wires 51 and 54 in the p¹ and p³ positions, respectively, of the lever, by reversing the polarity of the current supplied to the line wires 51 and 54 while the asymmetric unit R³ permits the desired selective control of the valves V² and V³ in the p⁴ and p⁵ positions of lever L to be obtained by reversing the polarity of the current supplied to the two line wires 62 and 54.

Although I have herein shown and described only two forms of railway braking apparatus embodying my invention, it is understood that various changes and modifications may be made therein within the scope of the appended claims without departing from the spirit and scope of my invention.

Having thus described my invention, what I claim is:

1. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a pneumatic transfer switch responsive to the pressure of the fluid in said motor and provided with a normally closed contact which becomes opened when the pressure of the fluid in said motor increases to a pressure which is somewhat less than the pressure of said low pressure source and with a normally open contact which becomes closed when said normally closed contact becomes opened, means controlled by said normally closed contact for connecting said motor with said first pipe, and means controlled by said normally open contact for connecting said motor with said second pipe.

2. Railway braking apparatus comprising a

braking bar extending parallel to a track rail, a fluid pressure motor for moving said braking bar toward said track rail to braking positions, a first pipe connected with a source of relatively low pressure fluid, a second pipe connected with a source of relatively high pressure fluid, a pneumatic transfer switch responsive to the pressure of the fluid in said motor and provided with a normally closed contact which becomes opened when the pressure of the fluid in said motor increases to a pressure which is somewhat less than the pressure of said low pressure source and with a normally open contact which becomes closed when said normally closed contact becomes opened, a manually operable contact, means controlled by said manually operable contact and said normally closed contact for connecting said motor with said first pipe, and means controlled by said manually operable contact and said normally open contact for connecting said motor with said second pipe.

3. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the pressure of the fluid in said motor and provided with a normally closed contact which becomes opened when the pressure of the fluid in said motor increases to a pressure which is somewhat less than the pressure of said low pressure source and with a normally open contact which becomes closed when said normally closed contact becomes opened, and means controlled by said two contacts for selectively controlling said two magnet valves.

4. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the pressure of the fluid in said motor and provided with a normally closed contact which becomes opened when the pressure of the fluid in said motor increases to a pressure which is somewhat less than the pressure of said low pressure source and with a normally open contact which becomes closed when said normally closed contact becomes opened, and means for at times energizing said first or said second magnet valve according as said normally closed or said normally open contact is closed.

5. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the pressure

- a second predetermined amount which is larger than said first predetermined amount, said transfer switch also being provided with a first contact which is closed when said contact operating member occupies said one position and with a second contact which is closed when said contact operating member occupies said other position, a circuit for said first magnet valve including said first contact, and a circuit for said second magnet valve including said second contact.
11. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the difference in pressure between the fluid in said motor and in said first pipe and provided with a contact operating member which moves from one position to another position with a snap action when the difference in pressure between the fluid in said motor and in said first pipe becomes less than a first predetermined amount and which returns to said one position with a snap action when the difference in pressure between the fluid in said motor and in said first pipe becomes greater than a second predetermined amount which is larger than said first predetermined amount, said transfer switch also being provided with a first contact which is closed when said contact operating member occupies said one position and with a second contact which is closed when said contact operating member occupies said other position, a manually operable contact, a circuit for said first valve controlled by said manually operable contact and said first contact, and a circuit for said second valve controlled by said manually operable contact and said second contact.
12. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first and a second contact, means for opening said first contact and for closing said second contact when the difference between the pressure of the fluid in said motor and in said first pipe becomes less than a first predetermined amount and for closing said first contact and for opening said second contact when the difference between the pressure of the fluid in said motor and in said first pipe becomes greater than a second predetermined amount which is more than said first predetermined amount, a pressure responsive device subjected to the pressure of the fluid in said motor and provided with a normally closed contact which becomes opened when the pressure of the fluid in said first pipe increases to a pressure which is a predetermined amount above the pressure of the fluid in said first pipe, means controlled by said first contact and said normally closed contact for connecting said motor with said first pipe, and means controlled by said second contact and said normally closed contact for connecting said motor with said second pipe.
13. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the difference between the pressure of the fluid in said motor and in said first pipe becomes greater than a second predetermined amount which is more than said first predetermined amount, a pressure responsive device subjected to the pressure of the fluid in said motor and provided with a normally closed contact which becomes opened when the pressure of the fluid in said first pipe increases to a pressure which is a predetermined amount above the pressure of the fluid in said first pipe, means controlled by said first contact and said normally closed contact for connecting said motor with said second pipe, and means controlled by said second contact and said normally closed contact for connecting said motor with said first pipe.
14. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, means for at times connecting said motor with said first pipe, a first magnet valve for connecting said motor with said second pipe, a second magnet valve for connecting said motor with atmosphere, a pneumatic transfer switch responsive to the pressure of the fluid in said motor and provided with a normally closed contact which becomes opened when the pressure of the fluid in said first pipe increases to a pressure which is a predetermined amount above the pressure of the fluid in said first pipe, a manually operable contact, a circuit for said first valve including said first contact, said normally closed contact, and said manually operable contact; and a circuit for said second valve including said second contact, said normally closed contact, and said manually operable contact.
15. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, means for at times connecting said motor with said first pipe, a first magnet valve for connecting said motor with said second pipe, a second magnet valve for connecting said motor with atmosphere, a pneumatic transfer switch responsive to the pressure of the fluid in said motor and provided with a normally closed contact which becomes opened when the pressure of the fluid in said first pipe increases to a pressure which is a predetermined amount higher than the pressure of the fluid in said first pipe and which subsequently remains opened until the pressure of the fluid in said motor decreases to a second pressure which is less than said first pressure but more than the pressure of the fluid in said first pipe, said switch also being provided with a second contact which becomes closed when said first contact becomes opened and opened when said first contact becomes closed, and means for energizing said first or said second magnet valve according as said second or said first contact is closed.
16. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, means for at times connecting said motor with said first pipe, a first magnet valve for connecting said motor with said second pipe, a second magnet valve for connecting said motor with atmosphere, a pneumatic transfer switch responsive to the pressure of the fluid in said motor and provided with a normally closed contact which becomes opened when the pressure of the fluid in said first pipe increases to a pressure which is a predetermined amount higher than the pressure of the fluid in said first pipe and which subsequently remains opened until the pressure of the fluid in said motor decreases to a second pressure which is less than said first pressure but more than the pressure of the fluid in said first pipe, said switch also being provided with a second contact which becomes closed when said first contact becomes opened and opened when said first contact becomes closed, and means for energizing said first or said second magnet valve according as said second or said first contact is closed.

fluid in said first pipe and which subsequently remains opened until the pressure of the fluid in said motor decreases to a second pressure which is less than said first pressure but more than the pressure of the fluid in said first pipe, said switch 5 also being provided with a second contact which becomes closed when said first contact becomes opened and opened when said first contact becomes closed, and means controlled by said two contacts for selectively controlling said two 10 valves.

16. Railway braking apparatus comprising a braking bar extending parallel to a track rail, a fluid pressure motor for moving said braking bar toward said track rail to braking positions, a first 15 pipe connected with a source of relatively low pressure fluid, a second pipe connected with a source of relatively high pressure fluid, means for at times connecting said motor with said first pipe, a first magnet valve for connecting said motor with said second pipe, a second magnet valve for connecting said motor with atmosphere, a first contact and a second contact, means for opening said first contact and for closing said second contact when the pressure of the fluid in said motor increases to a first pressure which is more than a predetermined amount above the pressure of the fluid in said first pipe and for closing said 20 first contact and for opening said second contact when the pressure of the fluid in said motor is between said first pressure and the pressure of the fluid in said first pipe, a pressure responsive device subjected to the pressure of the fluid in said motor and provided with a normally closed contact which becomes opened when the pressure of the fluid in said motor increases to a predetermined pressure which is less than the pressure of the fluid in said first pipe and with a normally open contact which becomes closed when the pressure of the fluid in said motor increases to a pressure which is somewhat higher than the pressure at which said normally closed contact opens, a first circuit for said first magnet valve including said normally closed contact, a second circuit for said first magnet valve including said second contact and said normally open contact, and a circuit for said second magnet valve including said first contact and said 30 normally open contact.

17. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a third magnet valve for connecting said motor with atmosphere, a first pneumatic transfer switch responsive to the difference in pressure between the fluid in said motor and in said first pipe and provided with a first contact operating member which moves from one position to another position with a snap action when the pressure of the fluid in said motor increases to a first pressure which is a predetermined amount below the pressure of the fluid in said first pipe and which returns to said one position with a snap action when the pressure of the fluid in said motor decreases to a second pressure which is below said first pressure, said first transfer

switch being provided with a first contact which is closed when and only when said first contact operating member occupies its one position and with a second contact which is closed when and only when said first contact operating member occupies its other position, a second pneumatic transfer switch responsive to the difference in pressure between the fluid in said motor and in said first pipe and provided with a second contact operating member which moves from one position to another position with a snap action when the pressure of the fluid in said motor increases to a third pressure which is a predetermined amount above the pressure of the fluid in said first pipe and which returns to said one position with a snap action when the pressure of the fluid in said motor decreases below a fourth pressure which is between said third pressure and the pressure of the fluid in said first pipe, said second transfer switch being provided with a third contact which is closed when and only when said second contact operating member occupies its one position and with a fourth contact which is closed when and only when said second contact operating member occupies its other position, means for at times energizing said first or said second magnet valve according as said first or said second contact is closed, and means for at other times energizing said second or said third valve according as said fourth or said third contact is closed.

18. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first pneumatic transfer switch responsive to the difference in pressure between the fluid in said motor and in said first pipe and provided with a first contact operating member which moves from one position to another position with a snap action when the pressure of the fluid in said motor increases to a first pressure which is a predetermined amount below the pressure of the fluid in said first pipe and which returns to said one position with a snap action when the pressure of the fluid in said motor decreases to a second pressure which is below said first pressure, said first transfer switch being provided with a first contact which is closed when and only when said first contact operating member occupies its one position and with a second contact which is closed when and only when said first contact operating member occupies its other position, a second pneumatic transfer switch responsive to the difference in pressure between the fluid in said motor and in said first pipe and provided with a second contact operating member which moves from one position to another position when the pressure of the fluid in said motor increases to a third pressure which is a predetermined amount above the pressure of the fluid in said first pipe and which returns to said one position with a snap action when the pressure of the fluid in said motor decreases below a fourth pressure which is between said third pressure and the pressure of the fluid in said first pipe, said second transfer switch being provided with a third contact which is closed when and only when said second contact operating member occupies its one position and with a fourth contact which is closed when and only when said second contact operating member occupies its other position.

- means for at times connecting said motor with said first or said second pipe according as said first or said second contact is closed, and means for at other times connecting said motor with 5 said first pipe or with atmosphere according as said fourth or said third contact is closed.
19. Railway braking apparatus comprising a braking bar adapted to engage a part of a railway car for retarding the speed of the car, a fluid 10 pressure motor for moving said braking bar to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the difference in pressure of the fluid in said motor and said low pressure source and provided with a first contact which becomes opened when the pressure of the fluid in said motor increases to a pressure which is somewhat less than the pressure of said low pressure source and with a second contact which becomes closed when said 20 first contact becomes opened, a third contact responsive to the pressure of the fluid in said motor and arranged to become opened when the pressure of the fluid in said motor increases to a pressure which is somewhat higher than the pressure which is somewhat higher than the pressure of said low pressure source, two line wires, means for reversibly supplying said line wires with current, means including said first contact and said third contact for at times connecting said first valve with said line wires, means including said second contact and an asymmetric unit for at still other times connecting said second valve 30 with said line wires.
20. Railway braking apparatus comprising a braking bar adapted to engage a part of a railway car for retarding the speed of the car, a fluid pressure motor for moving said braking bar to 45 braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the difference between the pressure of the fluid in said motor and said first pipe and provided with a first contact which becomes opened when the pressure of the fluid in said motor increases to a pressure which is somewhat less than the pressure of said low pressure source and with a second contact which becomes closed when said first contact becomes opened, a pressure responsive device subjected to the pressure of the fluid in said motor and provided with a normally closed contact which becomes opened when the pressure of the fluid in said motor increases to a pressure which is somewhat higher than the 60 pressure of said low pressure source and with a normally open contact which becomes closed at a pressure which is somewhat higher than the pressure at which said normally closed contact opens, two line wires, means for reversibly supplying said line wires with current, means including said normally closed contact and said first contact for connecting said first magnet valve with said line wires, means including said normally closed contact and said first contact for connecting said second magnet valve with said 70 line wires, means including said second contact and a first asymmetric unit for connecting said second magnet valve with said line wires, and means including said normally open contact and a second asymmetric unit for connecting said first magnet valve with said line wires.
21. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, a first magnet valve for connecting said motor with said first pipe, a second magnet valve for connecting said motor with said second pipe, a pneumatic transfer switch responsive to the difference in pressure between the fluid in said motor and in said first pipe and provided with a contact operating member which moves from one position to another position with a snap action when the difference in pressure between the fluid in said motor and in said first pipe becomes less than a first predetermined amount and which returns to said one position with a snap action when the difference in pressure between the fluid in said motor and in said first pipe becomes greater than a second predetermined amount which is larger than said first predetermined amount, said transfer switch also being provided with a first contact which is closed when said contact operating member occupies said one position and with a second contact which is closed when said contact operating member occupies said other position, a third contact responsive to the pressure of the fluid in said motor and arranged to become opened when the pressure of the fluid in said motor increases to a pressure which is somewhat higher than the pressure of said low pressure source, two line wires, means for reversibly supplying said line wires with current, means including said first contact and said third contact for at other times connecting said first valve with said line wires, and means including said second contact and an asymmetric unit for at still other times connecting said second valve with said line wires.
22. Railway braking apparatus comprising a braking bar extending parallel to a track rail, a fluid pressure motor for moving said braking bar toward said track rail to braking positions, a first pipe connected with a source of relatively low pressure fluid, a second pipe connected with a source of relatively high pressure fluid, means for at times connecting said motor with said second pipe, a first magnet valve for connecting said motor with said first pipe, a second magnet valve for connecting said motor with atmosphere, a pneumatic transfer switch responsive to the pressure of the fluid in said motor and provided with a first contact which becomes opened when the pressure of the fluid in said motor increases to a first pressure which is a predetermined amount higher than the pressure of the fluid in said first pipe and which subsequently remains opened until the pressure of the fluid in said motor decreases to a second pressure which is less than said first pressure but more than the pressure of the fluid in said first pipe, said switch also being provided with a second contact which becomes closed when said first contact becomes opened and opened when said first contact becomes closed, two line wires, means for reversibly supplying said line wires with current, means including said normally closed contact and said first contact for connecting said first magnet valve with said line wires, means including said normally closed contact and said first contact for connecting said second magnet valve with said line wires, and means including said normally open contact and a second asymmetric unit for connecting said first magnet valve with said line wires.

supplying said line wires with current, means including a first asymmetric unit and said first contact for at times connecting said second magnet valve with said line wires, means including 5 said first asymmetric unit and said second contact for at other times connecting said first magnet valve with said line wires, and means in-

cluding a second asymmetric unit for at still other times connecting said first valve with said line wires, said first and second asymmetric units being disposed in opposite directions with respect to said line wires.
